CLEVELAND H. QUACKENBUSH AND JAMES C. SMEDLEY, OF CLEVELAND, OHIO,
ASSIGNORS TO GENERAL ELECTRIC COMPANY, A CORPORATION OF NEW YORK.

WIRE-COILING APPARATUS.

1,227,659.

Specification of Letters Patent.

Patented May 29, 1917.

Application filed March 9, 1915, Serial No. 13,247. Renewed October 18, 1916. Serial No. 126,455.

To all whom it may concern:

Be it known that we, CLEVELAND H. QUACKENBUSH and JAMES C. SMEDLEY, citizens of the United States, residing at Cleveland, county of Cuyahoga, State of Ohio, have invented certain new and useful Improvements in Wire-Coiling Apparatus, of which the following is a specification.

Our invention relates to machines for winding wire into coils, and more specifically to machines for winding comparatively fine wire into close coils. Our invention is particularly adapted for making metal filaments of the coil type for use in incandescent lamps. These filaments are much used in cases where a concentrated light source is desired. It is necessary that the length of the wire be very accurately regulated in order that the resistance may be accurately fixed. It is desirable, also, that filaments of this kind be formed rapidly and in a manner calling for a minimum of manual attention. For this reason it is desirable to form a series of filaments from a continuous wire and to space the filaments apart. This necessitates a very accurate control of the winding mechanism. Moreover, it is desirable to have each filament composed of legs having plain portions between them, which portions are engaged by the filament supports in the lamp. This necessitates that the control for the winding mechanism be brought into operation at short intervals. The object of our invention is to provide an automatic machine for accomplishing the purposes set forth in a highly accurate and efficient manner.

According to our invention, the filament wire is fed through a measuring device, the speed of which corresponds accurately to that of the filament wire, and said device, through suitable mechanism, actuates means for stopping the winding and for starting it after a suitable interval. In its preferred form this mechanism comprises electrical make and break mechanism which controls suitable clutch and break mechanism included in the drive of the winding mechanism. On account of the fact that it is possible, by using a traveling mandrel, to cause a continuous operation of the machine and to form a continuous filament of any desired length without stopping the machine, I prefer to use such a mandrel and to rotate the filament wire thereupon, although it is ob-

vious that by suitable modification this arrangement might be reversed. Other features and advantages of our invention will appear from the detailed description thereof which follows, and from the accompanying drawing showing a specific embodiment thereof.

In the drawing, Figure 1 is a plan and Fig. 2 is an elevation, partially in section, of one form of a machine embodying our invention. Fig. 3 is a plan and Fig. 4 an elevation of a part of the wire measuring and control mechanism. Fig. 5 is a detail and Fig. 6 is a diagram of the electric circuits.

Referring now to the drawing, it will be seen that the machine comprises a bed 10 supported on suitable standards 11. Any suitable drive, such as the motor 12, mounted upon the bed 10, may be utilized. The mandrel wire 13 extends longitudinally of the machine and axially with respect to the shafts 14, which are journaled with roller bearings in the standards 15 mounted on the bed of the machine and which extend from each end of a rotary head or carrier 16. The aforesaid shafts and also the shaft 17, which is integral with the motor shaft, are bored axially so that the mandrel wire may extend therethrough. The mandrel wire 13 is caused to travel longitudinally at a predetermined speed so as to give the filament coil the desired pitch. As shown in the drawing, motion is communicated from the motor shaft to the countershaft 18 through the two-speed gear 19. The shaft 18 is connected by means of a two-speed gear 20 with a shaft 21. The rotation of the shaft 21 is communicated to a worm 22 through a multiple-speed transmission of a well known type, and comprising a series of gears 23, as shown, 12 in number, any one of which may be driven through a pinion 24 mounted in a holder 25 and engaging another pinion also mounted in said holder, and slidably splined on the shaft 21. The holder 25 is provided with an operating handle 26 and a lock 27 slideable upon a bar 28 in the front of the machine. The rotation of the worm 22 drives the gear 29 mounted in the U-shaped frame 30 and carrying peripherally grooved disk 31 around which the mandrel wire extends. The said disk may have also attached thereto a gear 32 which engages a pinion 33 and drives thereby a pair of rolls 110.

34, which frictionally engage the mandrel wire. It is obvious, however, that any suitable device may be substituted for these friction rolls provided the speed thereof corresponds to that of the disk 31.

5 The filament wire may be carried by a suitable holder, such as spool 35, mounted on the head 16. The filament wire 36 extends from the said spool across the stationary 10 guide 37, the part 37' of which engaging the filament wire may be of felt or other soft substance which will not wear the wire. The wire then extends around a grooved guide roll 38 and a measuring disk 39. The 15 said disk is peripherally grooved to receive the wire and is removably carried by the stud 40 supported in anti-friction bearings in the head 16. Various sizes of such disks may be used depending upon the size of the 20 wire and the pitch of the coils desired. The stud 40 carries a pinion 41 which engages with the peripherally toothed disk 42, which is rotatably supported in the head 16. Carried by or integral with the disk 42 is a disk 25 or disks, the periphery of which is formed into the cams 43 and 44, as shown in Figs. 3 and 4. Bearing against the upper cam 43 is one end 45 of a pawl 46 pivoted at 47 to the head 16. The other end is attached by 30 spring 48 to the said head. Below the pawl 46 is a pawl 49 also pivoted at 47 and having one end 50 engaging the cam 44. The other end of the pawl 49 carries the double 35 contact 51 which is adapted to engage either of the stationary contacts 52, 53. As shown in Figs. 3 and 4, a leaf spring 54 is attached to pawl 49 and to the pawl 46. The arrangement is such that when the end 45 of pawl 46 falls into an indentation in cam 43, the end 50 of pawl 49 is simultaneously 40 ejected from an indentation in cam 44, and, as the end 45 is forced gradually out of its indentation, the spring pressure upon the end 50 gradually increases until, at the instant end 45 leaves the indentation, end 50 is 45 forced into its indentation. It will be apparent, therefore, that the pawl 49 is always under pressure from the spring 54 and this causes it to operate instantly and to cause instantaneous shifting of the movable contact 51.

50 The contacts 52, 53 are in circuit respectively with the solenoids 52', 53'. The latter are mounted below the machine and control the armature 54 carried at the end of a lever arm 55 fulcrumed on the bed of the machine at 56 and carrying at its other end the rod 57 slidably mounted in the sleeves 58, which may extend from the standards 55. The said rods are attached to a mechanism comprising the brake 59 and the movable clutch member 60. The stationary 60 clutch member 61 is conical and so fashioned that its inner surface is engaged by the movable clutch member 60 and the brake 59.

It will be obvious that when the rods 57 are moved to the right the clutch will be thrown out and the brake brought into operation, while a movement to the left will cause the clutch to be thrown in and the brake to be thrown out. The movement of the pawl 49, caused by the cams before referred to, will cause the contact 51 to engage with the contact 52 or 53, as the case may be, and thus cause the rotation of the head 16 to be stopped or started instantaneously.

70 The electrical connections are shown diagrammatically in Fig. 6. Energy is obtained from a suitable source, such as motor-generator set 62. One terminal thereof is 80 connected in multiple with the coils 52', 53', which are connected respectively to metal straps 63, 64 engaging the rings 65, 66 respectively. These rings are shown in Figs. 1 and 2 and are mounted on the shaft of the 85 rotatable head 16. They are connected to the contacts 52 and 53 respectively. The movable contact 51 is connected to ring 67 mounted with the other rings and engaged by a strap 68 connected to the other terminal 90 of the generator.

95 It is preferred to heat the coiling end of the filament wire and this is most conveniently accomplished electrically. As shown in Fig. 6, the energy is obtained from transformer 69, to one terminal of which is connected a strap 70 engaging ring 71 mounted with the other rings hereinbefore described. Ring 71 is connected to post 72 carrying the spring clamp 73 engaging and serving to 100 hold the end of the filament wire against an insulating block 74. A metal block 75 engages the mandrel wire adjacent to the coiling end of the filament wire and this block is grounded. It will be apparent that the 105 heating current will pass through a short length of the filament wire at the coiling end.

110 The operation of the above described parts will be apparent. As soon as the machine is started the mandrel wire may be made to move at any desired speed to manipulate the various change speed mechanisms. The rotation of the head 16 will cause the filament wire to be unwound from 115 the spool 35 causing a rotation of the disk 39, the end of the filament wire adjacent to the mandrel will be heated. The size of the disk 39 is so chosen that the proper length of wire will be unwound to correspond to 120 the speed of the mandrel so as to obtain the proper length and, therefore, the proper amount of resistance of the filament. The rotation of the disk 39 will cause the cams 43 and 44 to rotate and thus to operate the 125 movable contact 51, and thus to intermittently stop the machine and start it again. This causes plain spaces to be formed between the coils, and it will be obvious that 130 this may occur as many times as desired,

since the speed at which the cams rotate will be determined by the size of the disk 39. It will be apparent, also, that in the

- 5 particular form which has been described it is possible to continue to wind the coil filament as long as the mandrel wire lasts. It will be apparent, also, that the operation of the machine is entirely automatic, requiring practically no attention except for placing 10 a new spool of filament wire in place or attaching a new reel of mandrel wire and removing that upon which the filament has been formed.

What we claim as new and desire to secure by Letters Patent of the United States, is:-

1. In a coiling machine, a mandrel wire and a coil wire carrier, means for rotating one of the same with reference to the other, 20 means for measuring the coil wire and for feeding it to the mandrel wire, and means automatically controlled by said feeding and measuring means for interrupting said relative movement at predetermined intervals.

- 25 2. In a coiling machine, a mandrel wire and a coil wire carrier, means for rotating one of the same with reference to the other, means for measuring the coil wire and for feeding it to the mandrel wire, and means 30 automatically controlled by said feeding and measuring means for interrupting said relative movement at predetermined intervals and for predetermined periods.

3. In a coiling machine, a mandrel wire and a coil wire carrier, means for rotating one of the same with reference to the other, means for measuring the coil wire and for feeding it to the mandrel wire, and electrical 40 means automatically controlled by said feeding and measuring means for interrupting said relative movement at predetermined intervals.

4. In a coiling machine, a mandrel wire and a coil wire carrier, means for rotating one of the same relatively to the other and means for measuring said coil wire and for feeding it to said mandrel wire, said means comprising a measuring disk around which the coil wire passes.

- 50 5. In a coiling machine, a mandrel wire and a coil wire carrier, means for rotating one of the same relatively to the other, means for measuring said coil wire and for feeding it to said mandrel wire, said means comprising a measuring disk around which the coil wire passes, and means controlled by the rotation of said disk for automatically interrupting the aforesaid relative movement at predetermined intervals.

- 60 6. In a coiling machine, a mandrel wire and means for causing the same to move longitudinally at a desired speed, a coil wire carrier and means for rotating the same around said mandrel wire, said carrier comprising means for measuring said coil wire

and for feeding the same to said mandrel wire.

7. In a coiling machine, a mandrel wire and means for causing the same to move longitudinally at a desired speed, a coil wire 70 carrier and means for rotating the same around said mandrel wire, said carrier comprising means for measuring said coil wire and for feeding the same to said mandrel wire, means automatically controlled by 75 said feeding and measuring means for interrupting said rotation at predetermined intervals.

8. In a coiling machine, a mandrel wire and means for causing the same to move longitudinally at a desired speed, a coil wire 80 carrier and means for rotating the same around said mandrel wire, said carrier comprising means for measuring said coil wire and for feeding the same to said mandrel wire, and means automatically controlled 85 by said feeding and measuring means for interrupting said rotation at predetermined intervals and for predetermined periods.

9. In a coiling machine, a mandrel wire 90 and means for causing the same to move longitudinally at a desired speed, a coil wire carrier and means for rotating the same around said mandrel wire, said carrier comprising means for measuring said coil wire 95 and for feeding the same to said mandrel wire, and electrical means automatically controlled by said feeding and measuring means for interrupting said rotation at predetermined 100 intervals and for predetermined periods.

10. In a coiling machine, a mandrel wire and means for causing the same to move longitudinally at a desired speed, a coil wire carrier and means for rotating the same 105 around said mandrel wire, said carrier comprising means for measuring said coil wire and for feeding the same to said mandrel wire, a measuring disk around which the coil wire passes and means controlled by the 110 rotation of said disk for interrupting said rotation at predetermined intervals.

11. In a coiling machine, a mandrel wire and means for causing the same to move longitudinally at a desired speed, a coil wire 115 carrier and means for rotating the same around said mandrel wire, said carrier comprising means for measuring said coil wire and for feeding the same to said mandrel wire, a measuring disk around which the 120 coil wire passes and electrical means controlled by the rotation of said disk for interrupting said rotation at predetermined intervals.

12. In a coiling machine, a mandrel wire 125 and means for causing the same to move longitudinally at a desired speed, a coil wire carrier and means for rotating the same around said mandrel wire, a clutch and brake mechanism included in said rotating means, 130

means for measuring the coil wire and feeding it to said mandrel and means automatically controlled by said feeding and measuring means for operating said clutch and brake mechanism at predetermined intervals.

13. In a coiling machine, a mandrel wire and means for causing the same to move longitudinally at a desired speed, a coil wire carrier and means for rotating the same around said mandrel wire, a clutch and brake mechanism included in said rotating means, means for measuring the coil wire and feeding it to said mandrel and electrical means automatically controlled by said feeding and measuring means for operating said clutch and brake mechanism at predetermined intervals.

14. In a coiling machine, a mandrel wire and means for causing the same to move lon-

gitudinally at a desired speed, a coil wire 20 carrier and means for rotating the same around said mandrel wire, a clutch and brake mechanism included in said rotating means, means for measuring the coil wire and feeding it to said mandrel and means 25 automatically controlled by said feeding and measuring means for operating said clutch and brake mechanism at predetermined intervals, said means including an electric make and break device and a cam 30 for operating the same.

In witness whereof, we have hereunto set our hands this 6th day of March, 1915.

CLEVELAND H. QUACKENBUSH.

JAMES C. SMEDLEY.
